UNITED STATES PATENT OFFICE.

CLARENCE M. CREWS, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed December 14, 1923. Serial No. 620,607.

This invention relates to means in a type-writing machine for producing a condensed record of a succession of typed bills or other documents. More particularly, it relates to 5 condensed record mechanism in a continuous billing machine, the condensed record being produced by the omission from the record-web of the items written in the headings of the bills which are not required on the record, and by causing the items written in the bodies of successive bills to follow each other closely on the record-web without long intervening blank spaces corresponding to the heading spaces. 10 The continuous billing machine usually includes a carbon-carrier movable along a carriage-extension toward and from the platen. A succession of bills with related duplicate forms, printed upon the plies of a continuous fan-fold web, or upon superposed 15 separate web-plies, is introduced into the continuous billing machine at the rear and led forward through the carbon-carrier to be interleaved with the carbons thereof. The web with the interleaved carbons passes forward around the revoluble platen, which is displaceable to permit straightening of the webs and carbons, so that the carbons may be withdrawn from the forms of a typed 20 web-section and interleaved with the next succeeding section by pushing the carbon-carrier to the rear. It is frequently desirable to keep a composite record of the bills written, for which purpose a continuous 25 record-web is provided to run between the platen and the multiple-ply work-web to receive impressions through the innermost carbon held by the carbon-carrier. 30

The bills generally have long printed display headings, and ordinarily receive only 40 a few typed items in their headings which it is unnecessary to reproduce on the record-web, or for which a name or number in a protruding margin of the record-web might well be substituted. In some cases, too, no 45 typing is done on the heading, the name and address of the customer being stenciled thereby by means of a stenciling machine.

In accordance with the present invention, 50 the items written in the heading portion of each bill, or so much thereof as are not wanted on the record-web, are caused to be omitted from the record-web by making the carbon-sheet (carried by the carbon-carrier of the machine), for printing on the record-

web, shorter than the other carbons, and so short that it will not reproduce the heading items not wanted on the record-web.

The record-web is fed forward with the bill-webs, however, while the heading is being typed or while the platen is being rotated to advance the bill-web from web-severing position to position for the writing of items in the body of a bill, and this would cause gaps to appear on the record-web corresponding to the spaces occupied by the headings of the bills if provision were not made to avoid this result. In order that the body-portions of the bills reproduced on the record-web may be written 70 close to each other, provision is made of means for shifting the record-web backward relatively to the bill-web a distance roughly equal to the length of the bill heading after the completion of each bill. Such means 75 may comprise feed-rolls for the record-web mounted on the carriage-extension of the machine above the path of the carbon-carrier, a pinion on one of the rolls, and a rack on the carbon-carrier handle to pick 80 the pinion up and drive it in the course of the rearward movement of said handle. The record-web is thus automatically collated with reference to the bill-web without any 85 attention from the operator.

In accordance with one feature of the invention, the rack may be adjustably mounted on the carbon-carrier handle to cause it to engage the pinion early or late in its travel, and thereby impart to the record-web the exact amount of backward feeding required, according to the needs of the particular work. A uniform adjustment of the rack is required for all the forms of a given 90 style, and hence readjustment of the rack is 95 seldom necessary.

It is an important feature of the invention that the gearing for driving the record-web feed-rolls is so designed that the peripheral speed of the rolls is exactly the 100 same as the speed at which the carbon-carrier is moved. As a result of this arrangement, the condensed record-web is retracted by the rolls in unison with the carbons, and is yielded up by the rolls at the same rate at 105 which the bill-web and carbons are drawn forward by the platen at the lowering of the platen and in that portion of the writing operation during which the pinion and rack are in mesh.

A feature of the invention consists in the combination with the record-web feed-rolls of side guides at the rear of the carriage-extension for co-operation with the feed-rolls to guide the record-web to the platen and to control the record-web when the platen is displaced. The web is detained and controlled against accidental displacement in line-feed direction by the rolls and against skewing or sidewise displacement, the side guides contributing to the latter result. It will be understood, however, that the control against line-feeding is yielding, and that the operator can, if he so desires, draw the record-web forward or backward while the rack and pinion are disengaged, without affecting the bill-web or the carbons.

Other features and advantages will hereinafter appear.

In the accompanying drawings,

Figure 1 is a sectional side elevation, showing the work in writing position with the writing line near the bottom of the body of a bill.

Figure 2 is a view similar to Figure 1, but showing the platen displaced, the work drawn forward for gaging, and the carbon-carrier retracted.

Figure 3 is a vertical transverse section on the line 3—3 of Figure 1, looking in the direction of the arrows.

Figure 4 is a vertical transverse section on the line 4—4 of Figure 1, looking in the direction of the arrows.

Figure 5 is a diagrammatic view illustrating the bill-web and record-web side by side, and showing how the items written in the bodies of the three successive bills appear on the condensed record-web.

In the continuous billing machine, which may be of the type disclosed in the patent to Wernery & Smith, No. 1,132,055, granted March 16, 1915, types 10 swing upwardly and rearwardly to strike against the front of a revolute platen 11, journaled by its axle 12 in a swing-frame 13 mounted in a traveling carriage 14. A multiple-ply bill-web 19 is introduced into the machine over a rear bar 15 of a carriage-extension 16, comprising rails 17 on which a carbon-carrier 18 is reciprocable toward and from the platen. The bill-web 19 is interleaved with the carbons 20 carried by the carbon-carrier 18, and passes forward with them around the platen 11, and upward over a front paper-table 21 forming part of the swing-frame 13. At line-spacing, the carbon-carrier 18 advances with the bill-web 19 toward the platen 11, and, when a bill A has been completely typed, the swing-frame 13 is rotated about its axis 22 to raise the platen and thus permit straightening of the webs, so that they may be drawn forward to a gage 23 and the carbons may be retracted by

thrusting the carbon-carrier handle 24 backward to move the carbon-carrier 18 to the rear.

For the purpose of providing a composite record of the bills, a continuous record-web 25 separate from the multiple-ply bill-web 19 is introduced into the machine from the rear and passed around the platen in back of the bill-web and in position to receive impressions from the innermost carbon 26 carried by the carbon-carrier 18. At the delivery side of the platen the record-web 25 is directed to the rear of the front paper-table 21, so that it is not drawn forward to the gage 23 with the bill-web 19 but remains stationary during this operation. Neither is it torn off with the bill-web when the latter is drawn against the knife 27 after gaging.

In accordance with the present invention, the innermost carbon 26 of the carbon-carrier 18, which prints upon the record-web 25, is made shorter than the other carbons 20 by substantially the length of the heading portion of a bill. In the fully retracted position of the carbon-carrier 18, therefore, and when the bill-web is drawn forward to the gage, the leading edge of the carbon 26 extends to the line of division between the heading B₁ and body B₂ of the second bill B on the web 19. By thus arranging the carbon 26, the items subsequently written in the heading B₁ of the bill B (if any are written there) are caused to be omitted from the record-web. The record-web 25, however, is line-fed with the bill-web 19 while the heading B₁ is being typed or while the platen is being turned to advance the bill B from severing position to position for typing its body-portion, and hence the natural result of omitting the heading items from the record-web 25 would be to cause gaps corresponding in length to the bill headings to appear on the record-web. To avoid these useless gaps, provision is made of means for retracting the record-web 25 a predetermined uniform distance at the conclusion of each bill, so as to cause the first item of a bill reproduced on the record-web to lie a definite short distance below the last item of the previous bill appearing thereon. To this end, provision is made of record-web feed-rolls 28 and 29 mounted upon brackets 30 and 31 on the carriage-extension for feeding the record-web 25 to the rear as the carbon-carrier 18 is retracted. The upper roll 29 has its axle 32 journaled in arms 33 fast on a rock-shaft 34, journaled in the brackets 30 and 31, and is yieldingly pressed into engagement with the lower roll 28 by a torsion spring 35 encircling the rock-shaft 34, and having its opposite ends 36 and 37 engaged, respectively, with one of the arms 33 and with a stop 38 on the bracket 30. A finger-piece 39 fast to the rock-shaft 34 may

be operated to swing the upper roll 29 away

from the lower roll 28 to permit the introduction of the record-web 25 between the rolls. The lower roll 28 is fast upon its shaft 40, which also has a pinion 41 of the same effective diameter as the roll 28 fast upon it. This pinion 41 is located in position to be engaged and rotated by a rack 42, secured upon the carbon-carrier handle 24, in the course of the rearward movement thereof, to rotate the rolls 28 and 29 in a direction to retract the record-web 25. The rack 42 is secured upon the carbon-carrier handle 24 by screws 43, which are threaded into openings 44 in the carbon-carrier handle 24. It is important that the amount of rotation imparted to the record-web feed-rolls 28 and 29 be adjusted in accordance with the length of the bill heading. Accordingly, a multiplicity of threaded openings 44 is provided in the carbon-carrier handle 24 to permit a wide range of adjustment of the rack 42 on the handle 24, so that the rack may be caused to pick the pinion up early or late in its rearward movement to rotate the rolls. The pinion teeth may advantageously be arranged at line-space intervals, since the disposition of the pinion teeth for engagement with the rack will thus be kept uniform regardless of the extent of the line-feeding effected while the rack and pinion are disengaged.

The carbon-carrier 18 is apt to be rather loose on the rails 17, and hence to permit vertical play of the carbon-carrier handle 24 and so cause the meshing of the rack 42 and pinion 41 to be more or less haphazard. To guard against this, provision is made of an angle bar 45, having a vertical portion 46 secured to the carbon-carrier handle 24, and a horizontal flange 47 which passes snugly between guide-rolls 48 on the bracket 30 to steady the carbon-carrier handle. The angle bar 45 serves the further function of stiffening the carbon-carrier handle 24 so as to prevent side sway thereof.

As herein shown, the condensed record-web 25 is substantially wider than the bill-web 19 (see Figures 3, 4 and 5), the purpose being to provide a protruding right margin of the record-web 25 in which identifying data may be written, if necessary, in lieu of the omitted heading items. Side guides 49 and 50 are provided on the rear bar 15 for the wide record-web 25, these guides having horizontally-extending fingers 51 to overlie the margins of the record-web and hold it down to the guides. There is also provided on the bar 15, between the side guides 49 and 50, a side guide 52 of less height for the right edge of the narrow bill-web 19, and this guide 52 is also provided with a horizontally-extending finger 53 to hold the web down to the short guide 52. The rear side guides 49 and 50 for the record-web 25, acting in conjunction with the

record-web feed-rolls 28 and 29, serve effectually to guard against skewing or other misplacement of the record-web while the platen 11 is displaced.

At the conclusion of typing a bill, the platen is displaced, and this creates a slack in the bill and record webs (see Figure 2). The bill-web 19 is drawn forward to the gage 23, thus locating the leading edge of the second bill B on the web 19 in register with the edge of the knife 27. The carbon-carrier 18 is then moved to the rear to retract the carbons. This locates the leading ends of the long carbons 20 a short distance to the rear of the edge of the knife 27, and of the line of division between the first and second bill forms A and B on the web 19, and locates the leading edge of the short carbon 26 coincident with the line of division between the heading B₁ and the body B₂ of the second bill B on the web 19. At the same operation, due to the adjustment of the rack 42 on the carbon-carrier, the pinion 41 is picked up by the rack at such a stage that the record-web 25 is retracted to locate the last item typed thereon substantially two line-spaces in advance of the body B₂ of the second bill. The extent of this retraction should be equal to the amount of the slack in the record-web, plus the length of the bill heading, minus the distance from the knife edge to the line of writing, and minus the two line-spaces or other interval desired to be left on the record-web between the items of successive bills. Since all of these distances are unvarying for a given machine and a given style of bill, no readjustment of the rack is ordinarily required. Should it be desired to provide an exceptionally long space on the record-web between the items of two of the bills, this may obviously be done by rotating the platen forward prior to its displacement, or by drawing the record-web forward while the rack and pinion are disengaged and the platen is displaced.

The normal operation is illustrated diagrammatically in Figure 2, in which the point a indicates the position occupied by the first line of a bill reproduced on the record-web prior to the retraction of the carbon-carrier, the record-web being in a slack condition as indicated in dot-and-dash lines, and point a' indicates the retracted position of such a line, the slack having been taken out of the web. The point b indicates the retracted position of the last line of writing of the completed bill, and the point c indicates the position on the record-web which will be occupied by the next line that will appear on the record-web; viz, the first item written in the body B₂ of form B.

When bill-forms of a different length are to be used, the gage 23 and the stop 54 for limiting retraction of the carbon-carrier 18

are adjusted accordingly. The latter adjustment changes also the distance that the rack 42 travels in engagement with the pinion 41, and hence the rack will ordinarily require 5 readjustment also regardless of whether the length of heading is the same or different.

At Figure 5 a stretch of the bill-web showing the way the typed items appear upon three successive bills A, B and C, is shown 10 alongside a stretch of the record-web showing reproduction of the same bills thereon. The names "T. Brown", "J. Smith" and "R. Jones" are symbolical of the addresses or other heading items of the bills A, B and C, 15 respectively. These, it will be noticed, are omitted from the record-web, while the items indicated by X X X in the body of bill A are reproduced on the record-web and are followed with an interval of about two line- 20 spaces by the items O O O, reproduced from the body of bill B, and these, in turn, are followed after a two-line-space interval by the items — — — of bill C. The names "T. Brown", "J. Smith" and "R. Jones", 25 appearing in the right margin of the record-web, symbolize identifying data of the bills A, B and C, respectively, which may be typed on the protruding margin of the record-web in lieu of the heading items.

30 Variations may be resorted to within the scope of the invention, and portions of the improvements may be used without others.

Having thus described my invention, I claim:

35 1. In a machine for collating and typing upon a bill-web and a record-web with carbons interleaved between the web-plies, in combination, a revoluble platen, means to shift the interleaved carbons relatively to the webs, means to locate the bill-web in a new writing position with reference to the platen between the typing of bills, and re-collating means for imparting to the record-web a movement of mechanically predetermined extent relatively to the bill-web to 40 locate the record-web in a new predetermined relation to the platen and to the bill-web.

50 2. In a typewriting machine, in combination, a revoluble platen, writing instrumentalities to write upon a bill-web and to make impressions simultaneously upon a record-web by means of carbons interleaved with the web-plies, work-feeding means co-operating with the platen, means to free the record-web from the platen and feeding means to permit readjustment of the record-web relatively to the bill-web, means to effect relative shifting between the web-plies 55 and interleaved carbons, and means operable to retract the record-web while it is free of the platen and the work-feeding means, said record-web retracting means being constructed to automatically control the extent of said retraction.

3. In a continuous billing typewriting machine for typing upon a succession of bills and at the same time typing upon a record-web a composite record of items 70 typed on the bills, in combination, a revoluble platen displaceable to free the webs, a carbon-carrier reciprocable toward and from the platen, means for gaging the bill-web at the conclusion of each bill, means for retracting the carbon-carrier to shift the carbons relatively to the work, and automatically acting collating means for shifting the record-web into predetermined relation to the gaged bill-web without attention from the operator.

75 4. In a continuous billing typewriting machine for typing upon a succession of bills and at the same time typing upon a record-web a composite record of items typed on the bills, in combination, a revoluble platen displaceable to free the webs, a carbon-carrier reciprocable toward and from the platen, means for gaging the bill-web at the conclusion of each bill, means 80 for retracting the carbon-carrier to shift the carbons relatively to the work, and automatically acting collating means for shifting the record-web into predetermined relation to the gaged bill-web without attention from the operator.

85 5. In a continuous billing typewriting machine for typing upon a succession of bills and at the same time typing upon a record-web a composite record of items typed on the bills, in combination, a revoluble platen displaceable to free the webs, a carbon-carrier reciprocable toward and from the platen, means for gaging the bill-web at the conclusion of each bill, means 90 for retracting the carbon-carrier to shift the carbons relatively to the work, and means automatically actuated by the retraction of the carbon-carrier for collating the record-web with reference to the bill-web.

95 6. In combination, a displaceable revoluble typewriter platen, a carbon-carrier reciprocable toward and from the platen, long carbons on the carbon-carrier for writing upon the plies of the bill-web, a carbon on the carbon-carrier too short to reproduce 100

105 the record web the matter typed in the headings of the bill-web, a gage to which the bill-web is advanced to locate the typed first form in position for severing, a knife for severing the typed bill-web section, means for retracting the carbons a form length relatively to the bill-web, and positive means for retracting the record-web at the same time to a predetermined extent.

110 7. In combination, a displaceable revoluble typewriter platen, a leading-edge gage for the bill-forms, a carbon-carrier reciprocable toward and from the platen having full carbons for the bill-web and a short carbon for the record-web, and positive 115 means for retracting the record-web relative to the bill-web.

120 125 130

tively to the bill-web while the platen is displaced.

8. In a continuous billing typewriting machine for typing upon a succession of bills and at the same time typing upon a record-web a composite record of items typed on the bills, in combination, a revolute platen displaceable to free the webs, a carbon-carrier reciprocable toward and from the platen, means for gaging the bill-web at the conclusion of each bill, means for retracting the carbon-carrier to shift the carbons relatively to the work, record-web feed-rolls for feeding the record-web backward, and operating connections between the carbon-carrier and said feed-rolls to cause the feed-rolls to be fed backward automatically at the retraction of the carbon-carrier.

9. In a continuous billing typewriting machine for typing upon a succession of bills and at the same time typing upon a record-web a composite record of items typed on the bills, in combination, a revolute platen displaceable to free the webs, a carbon-carrier reciprocable toward and from the platen, means for gaging the bill-web at the conclusion of each bill, means for retracting the carbon-carrier to shift the carbons relatively to the work, record-web feed-rolls for feeding the record-web backward, operating connections between the carbon-carrier and said feed-rolls, effective automatically at a predetermined stage in the retraction of the carbon-carrier to impart a measured backward feeding to the record-web, and means for adjusting said connections to vary the stage at which they become effective.

10. In a continuous billing typewriting machine for typing upon a succession of bills and at the same time typing upon a record-web a composite record of items typed on the bills, in combination, a revolute platen displaceable to free the webs, a carbon-carrier reciprocable toward and from the platen, means for gaging the bill-web at the conclusion of each bill, means for retracting the carbon-carrier to shift the carbons relatively to the work, record-web feed-rolls, a pinion fast to one of the rolls, and a rack on the carbon-carrier, said rack being movable into operative relation with the pinion in the course of the retraction of the carbon-carrier to retract the record-web.

11. In a continuous billing typewriting machine for typing upon a succession of bills and at the same time typing upon a record-web a composite record of items typed on the bills, in combination, a revolute platen displaceable to free the webs, a carbon-carrier reciprocable toward and from the platen, means for gaging the bill-web at the conclusion of each bill, means for retracting the carbon-carrier to shift the carbons relatively to the work, record-web feed-rolls, a

pinion fast to one of the rolls and of the same effective diameter as said roll, and a rack on the carbon-carrier movable into operative relation with the pinion in the course of the retraction of the carbon-carrier to retract the record-web, the arrangement being such that the record-web is retracted at the same speed as the carbon-carrier.

12. In a continuous billing typewriting machine for typing upon a succession of bills and at the same time typing upon a record-web a composite record of items typed on the bills, in combination, a revolute platen displaceable to free the webs, a carbon-carrier reciprocable toward and from the platen, means for gaging the bill-web at the conclusion of each bill, means for retracting the carbon-carrier to shift the carbons relatively to the work, record-web feed-rolls, a pinion fast to one of the rolls and of the same effective diameter as said roll, the pinion teeth being arranged at line-space intervals, and a rack on the carbon-carrier movable into operative relation with the pinion in the course of the retraction of the carbon-carrier to retract the record-web, the arrangement being such that the record-web is retracted by the feed-rolls at the same speed at which the carbon-carrier moves and is given up by the feed-rolls in unison with the advance of the carbon-carrier, and such that the pinion is turned exactly a tooth-space at each line-spacing of the platen after the rack has left engagement with the pinion in the forward movement of the carbon-carrier.

13. In a continuous billing typewriting machine for typing upon a succession of bills and at the same time typing upon a record-web a composite record of items typed on the bills in combination, a revolute platen displaceable to free the webs, a carbon-carrier movable toward the platen at line-spacing and having a handle for retracting it when the webs are free, means for gaging the bill-web at the conclusion of each bill, record-web feed-rolls for feeding the record-web backward during retraction of the carbon-carrier, a pinion fast to one of the feed-rolls, a rack on the carbon-carrier handle to pick up the pinion and thereby rotate the feed-rolls, and means for securing the rack in any one of a multiplicity of positions on the carbon-carrier handle to vary the extent of the backward feeding of the record-web.

14. In a continuous billing typewriting machine for typing upon a succession of bills and at the same time typing upon a record-web a composite record of items typed on the bills, in combination, a revolute platen displaceable to free the webs, a carbon-carrier movable toward the platen at line-spacing and having a handle for retracting it when the webs are free, means for gaging

the bill-web at the conclusion of each bill, record-web feed-rolls for feeding the record-web backward during retraction of the carbon-carrier, a pinion fast to one of the feed-rolls, a rack on the carbon-carrier handle to pick up the pinion and thereby rotate the feed-rolls, the carbon-carrier handle having a multiplicity of threaded openings therein, and screws for co-operating with selected openings to secure the rack in selected positions on the carbon-carrier handle.

15. In a continuous billing typewriting machine for typing upon a succession of bills and at the same time typing upon a record-web a composite record of items typed on the bills, in combination, a revolute platen displaceable to free the webs, a carbon-carrier reciprocable toward and from the platen, means for gaging the bill-web at the conclusion of each bill, means for retracting the carbon-carrier to shift the carbons relatively to the work, record-web feed-rolls, a pinion fast to one of the rolls, a rack on the carbon-carrier, said rack being movable into operative relation with the pinion in the course of the retraction of the carbon-carrier to retract the record-web, and a horizontal flange on the carbon-carrier handle to guide and support the rack in engagement with the pinion.

16. In a machine for manifolding upon a main bill-web and at the same time typing upon a record-web a condensed record of items typed on the bills, in combination, a revolute platen displaceable to free the webs, releasable feeding means for pressing the bill-web and record-web against the platen, a carbon-carrier reciprocable toward and from the platen, means for gaging the bill-web at the conclusion of each bill, means for retracting the carbon-carrier to shift the carbons relatively to the work, a feed-roll couple for retracting the record-web, and side guides to engage the side edges of the record-web and guide it to the desired field of the platen, the record-web feed-roll couple and side guides co-operating to prevent skewing or other accidental misplacement of the record-web when said web is released by the displacement of the platen.

17. In a continuous billing typewriting machine for typing upon a succession of bills and at the same time typing upon a record-web a composite record of items typed on the bills, in combination, a revolute platen displaceable to free the webs, a leading-edge gage to which the bill-web may be drawn when freed by the displacement of the platen, a carbon-carrier advanceable toward the platen at line-spacing and retractable to shift the carbons relatively to the work-webs, a stop to limit retraction of the carbon-carrier, mechanism operated by the carbon-carrier in the course of its retracting movement to shift the record-web relatively to the bill-web, the leading edge gage and the carbon-carrier stop being adjustable to accommodate the machine to bills of different lengths, and means for adjusting the record-web-shifting mechanism to produce the desired extent of record-web shifting regardless of the adjusted position of the carbon-carrier-retracting stop.

18. In a typewriting machine, in combination, a displaceable revolute platen, a carbon-carrier reciprocable toward and from the platen, for use with long carbons on the carbon-carrier for writing upon the plies of the bill-web and a relatively short carbon on the carbon-carrier which is of insufficient length to reproduce on the record-web the matter typed in the headings of the bill-web, a gage to which the bill-web is advanced to locate the typed first form in position for severing, a knife for severing the typed bill-web section, means for retracting the carbons a form-length relatively to the bill-web, and positive means for retracting the record-web at the same time to a predetermined extent.

19. In a typewriting machine, in combination, a displaceable revolute platen, a leading-edge gage for the bill-forms, a carbon-carrier reciprocable toward and from the platen for carrying full carbons for the bill-web and also a short carbon for the record-web, and positive means for retracting the record-web relatively to the bill-web while the platen is displaced.

CLARENCE M. CREWS.
